UNITED STATES PATENT OFFICE.

JOHN L. BROWN, OF MOMENCE, ILLINOIS.

AEROPLANE-STABILIZER.

1,171,698.

Specification of Letters Patent.

Patented Feb. 15, 1916.

Application filed June 29, 1915. Serial No. 37,024.

To all whom it may concern:

Be it known that I, JOHN L. BROWN, a citizen of the United States, residing at Momence, in the county of Kankakee and State of Illinois, have invented new and useful Improvements in Aeroplane-Stabilizers, of which the following is a specification.

My invention relates to stabilizers for aeroplanes or flying machines of the heavier-than-air-type, and particularly to stabilizers for maintaining the lateral stability of such craft.

The object of the invention is to provide novel and improved stabilizing means whereby certain advantages are gained as hereinafter fully described.

In the drawings hereto attached and forming a part of this specification, Figure 1 is a front elevation of a biplane embodying my invention, showing in dotted lines one of the stabilizing planes adjusted for a balancing action. Fig. 2 is a top plan view of the same. Figs. 3 and 4 are opposite end elevations with parts appearing as in Fig. 1. Fig. 5 is a perspective view of one of the stabilizing planes. Figs. 6 and 7 are views illustrating the balancing actions.

In the accompanying drawings, for purposes of exemplification, I have shown the application of my invention to a biplane structure, for which it is best adapted, but it will, of course, be understood that the invention is not restricted to such application, as it is susceptible of application to and efficient use upon other types of heavier-than-air flying machines.

In the drawings, 1 and 2 designate the upper and lower main planes comprising the supporting surface of a biplane flying machine, which planes are connected as usual by the struts or stanchions 3 and the reinforcing wires or stays 4. In the construction of machine shown, the upper plane is of greater length or spread than the lower plane, having the laterally extending end portions 5 and 6 which project beyond the adjacent ends of the lower plane, but, while this construction is preferred, its use is not obviously essential.

In accordance with my invention, I provide a stabilizer comprising a pair of small stability planes 7 and 8, which are arranged respectively, at the right and left hand sides of the machine. These planes are counter-parts of one another; and each may be of any suitable construction, but in the form

shown consists of a suitable frame 8 having a fabric covering 9, the said plane being of concavo convex form between its front and rear edges, 10 designating the concaved face 60 or surface of the plane and 11 the convex surface thereof.

One (the forward) longitudinal edge of each plane is provided, with journals 12 which may constitute continuations of the 65 front spar of the frame thereof, and these journals 12 engage bearing members or eyes 13 upon the respective main planes 1 and 2, whereby the stability plane is pivotally mounted. Attached to the rear longitudinal 70 edge of the stability plane is a controlling cord or cable, the cords or cables 14 and 15 of the respective planes 7 and 8 passing forwardly and inwardly to a point in proximity to the aviator's seat 16 where they are 75 connected with a suitable control device or lever 17. The lever 17 shown in the present instance is mounted to swing laterally of the machine and when moved in one direction draws upon the cord 14 and relaxes the cord 80 15, and when moved in the opposite direction draws upon the cord 15 and slackens the cord 14.

It will be observed that the planes 7 and 8 extend between the marginal rear edges of 85 the main planes 1 and 2, and lie normally at an angle of 45° to the horizontal line of flight, in which position the stability planes are neither horizontal nor vertical, and partake neither of the nature of a horizontal 90 rudder or of the nature of a vertical rudder. The pivoted edges of the stability planes face forwardly, and owing to their described angle of inclination, the planes are absolutely neutral so far as their balancing or 95 stabilizing actions are concerned when in normal position, the planes lying simply so as to cut through the air without exerting any resisting action whatever thereon. It will also be observed that the concaved sides 100 of the stability planes face inwardly, and that said planes when positively moved for a stabilizing action swing forwardly and upwardly and in a direction toward the center of the machine, the concaved sides of the 105 planes facing forwardly in such action to receive the pressure of the wind.

When the machine is in flight and becomes laterally unbalanced, the aviator operates the control device to pull or draw upon the 110 cable leading to the stability plane at the high side, thus swinging said plane in-

wardly to a resisting position, in which its concaved surface lies at an angle to the line of flight, its angle being such that the air striking the surface of the plane performs three functions, one being of an incidental character, whereby the balance of the machine will be restored and the machine also prevented from oscillating fore-and-aft on its vertical axis and also prevented from skidding laterally. For instance, if, as shown in Fig. 6, the right hand side of the machine should be the high or elevated side, and the stability plane 7 at that side should be adjusted, it will be evident that the air striking the inclined stability plane will exert a depressing action on that side of the machine, by which the balance of the machine will be restored. At the same time the plane will set up a resistance against the forward motion of the right hand side of the machine, but, owing to its angle of inclination, this resistance will be incidental, and not sufficient to cause fore-and-aft oscillation, its principal function in such action being that of preventing the machine from sliding off its course or skidding laterally and downwardly in the direction of the low side of the machine. In this operation it will, of course, be understood that the plane 7 only is adjusted, the cable 15 being slackened and allowing the plane 8 to be free to assume an entirely idle position under the equal wind pressures on opposite sides thereof. Similarly, when the machine becomes unbalanced in the opposite direction and its left hand side is elevated, the stabilizing plane 8 at that side is adjusted for a stabilizing action, while the plane 7 is allowed to float free so as to be wholly devoid of any controlling action whatever.

When the stability plane on the high side of the aeroplane is operated it not only lowers the high side, but the resistance of the air striking the stability plane will also check the speed of the high side and in doing so it will turn the aeroplane slightly in the direction of the high side, which will also aid in restoring the lateral equilibrium of the aeroplane, but the stability planes can not be used to turn the aeroplane in full circles in the air. An aeroplane embodying my invention differs from an aeroplane that has stability planes, since such an aeroplane must have a vertical rudder to turn the aero-

plane toward the left or right or to make 55 circles in the air.

It will thus be seen that by the use of the stability plane as described the objections to warping structures will be avoided, as well as the objectionable resistances and strains established, as in the use of ailerons, where opposite stability planes are simultaneously employed and adjusted to different positions to elevate and depress the opposite sides of the machine respectively, moreover, my improved stability planes insure a much more rapid and easy stabilizing action, which to a large extent avoids back and forth oscillations of the machine on its vertical axis, and entirely overcomes any tendency of the machine to slide or skid laterally. The advantages of the invention will therefore be apparent to those versed in the art.

I claim:—

1. In an aeroplane, a stabilizer comprising small planes arranged at the rear lateral margins of the aeroplane, said planes being concavo-convexly curved and said planes being set at angles of 45° in the lateral direction of the aeroplane so as to swing with their concaved sides forward upwardly and inwardly toward the center of the aeroplane, and means for so swinging the stabilizing plane at the high side and allowing the stability plane at the low side to swing neutrally in the path of the wind.

2. In an aeroplane, a stabilizer comprising small planes arranged at the rear lateral margins of the aeroplane, said planes being concavo-convexly curved and said planes being set at outward and upward angles of 45° in the lateral direction of the aeroplane so as to swing with their concaved sides forwardly, upwardly and inwardly toward the center of the machine, and means for operating said planes, said means being operative for adjusting the plane at the high side in the stated manner while permitting the plane at the low side to swing neutrally in the path of the wind.

In testimony whereof I affix my signature in presence of two witnesses.

JOHN L. BROWN.
